DESIGN FOR A TABLE LAMP

Arthur Alpert, New York, N. Y., assignor to Arthur Alpert Lamp Co., Inc., Brooklyn, N. Y., a corporation of New York

Application March 3, 1947, Serial No. 137,280

Term of patent 3½ years

(Cl. D48—20)

To all whom it may concern:

Be it known that I, Arthur Alpert, a citizen of the United States, residing at 965 Fifth Avenue, in the city of New York, county of New York and State of New York, have invented a new, original, and ornamental Design for a Table Lamp, of which the following is a specification, reference being had to the accompanying drawing, forming part thereof.

In the drawing, the figure is a perspective view of a table lamp, showing my new design.

The dominant features of my new design reside in the portions shown in full lines.

I claim:

The ornamental design for a table lamp, substantially as shown and described.

ARTHUR ALPERT.
